DESK SET

Carey G. Gregory, Los Angeles, Calif.

Original application June 10, 1938, Serial No. 213,056. Divided and this application October 21, 1939, Serial No. 300,635

9 Claims. (Cl. 120—59)

My invention relates broadly to desk sets and more particularly to an improved construction of desk set operating upon the principle of hydrostatic pressure for feeding ink to a dip pen well.

5 This application is a division of my application Serial Number 213,056, filed June 10, 1938, Patent Number 2,180,518, Nov. 21, 1939, for Desk set.

One of the objects of my invention is to provide an improved construction of hydrostatic desk set which facilitates quantity production at 10 relatively low cost.

Another object of my invention is to provide a construction of hydrostatic desk set formed from a minimum number of parts capable of 15 being molded from a variety of synthetic materials.

Another object of my invention is to provide a construction of moldable desk set having a minimum number of parts with the pen receiving 20 guide formed integrally with the molded structure of the desk set.

Still another object of my invention is to provide a construction of desk set operative upon the hydrostatic principle in which the quantity 25 of the ink supply in the receptacle into which a dip pen is adapted to be submerged is restricted in comparison with the quantity of ink supplied to the receptacle by the hydrostatic pressure.

Still another object of my invention is to provide a desk set having a minimum number of 30 interengaging parts and in which the line of division of the parts may be wholly obscured in the process of manufacture of the parts and a unitary appearance imparted to the desk set for improving the esthetic qualities thereof.

A still further object of my invention is to provide a construction of molded desk set in which a pressure equalizing aperture is molded directly into that part of the desk set which also 35 unites integrally with the pen receiving guide in the desk set.

Still another object of my invention is to provide a desk set formed from interfitting ceramic members that are joined and glazed so that the 40 annular seam between the members is substantially invisible.

Other and further objects of my invention reside in the improved construction of molded 45 desk set as set forth more fully in the specification hereinafter following by reference to the accompanying drawing in which:

Figure 1 is a side elevation of a desk set constructed in accordance with my invention; Fig. 2 50 is a central vertical longitudinal sectional view

of the desk set on an enlarged scale with parts broken away and showing certain of the parts in side elevation; Fig. 3 is a horizontal sectional view taken on line 3—3 of Fig. 2; Fig. 4 is a side elevational view of the base of the desk set after completion of the baking and finishing treatment showing the parts appearing as a single unit; Fig. 5 is a vertical sectional view through the base of the desk set taken substantially on line 5—5 of Fig. 1; and Fig. 6 is a cross-sectional 10 view similar to Fig. 2 showing the upper and lower portions of the base of the desk set illustrated in juxtaposition.

The improved desk set of my invention is the result of extended research and development in 15 the art of desk sets operating upon the principle of hydrostatic pressure of the class set forth in my Patents 2,026,529, granted January 7, 1936; 2,112,907, granted April 5, 1938; and 2,148,941, granted February 28, 1939.

In my improved construction of hydrostatic desk set, the parts are reduced in number by molding the principal parts integrally as a unit from synthetic moldable material. The pen receiving guide through which a dip pen is 25 adapted to be inserted is molded integrally with the top portion of the molded base structure. I have found that it is wholly unnecessary to construct the guide for the dip pen independently of the base structure for in the improved arrangement of my invention the socket constituting the pen guide is integrally molded with the upper portion of the base structure. The pressure equalizing port is molded directly into 30 the upper portion of the base structure. The central bore through which the threaded neck of the ink supply bottle extends is provided with screw threads molded directly into the material of the upper portion of the base and all bushings or threaded inserts or gaskets dispensed with in establishing connection between the ink supply bottle and the upper portion of the base.

The quantity of ink in the pool or reservoir into which the point of a dip pen is adapted to 45 be inserted is restricted in the improved construction of my invention so that a smaller quantity of ink is consumed than in hydrostatic desk sets of previous constructions and the smaller quantity of ink maintained in better writing condition than is the case when a larger quantity of ink is maintained in the ink pool. The parts of the desk set are molded from synthetic material of various kinds such as Resinox, Tenite, porcelain, Bakelite and other phenol condensa- 50 55

tion products. I may mold the parts of the desk set from glass or other transparent material. Two principal parts are required; that is, the lower base portion which receives the ink supply and the upper base portion which provides telescopic interengagement with the lower base portion. In constructions where the division between the upper and lower portions of the base is substantially transverse, the exterior 10 cylindrical wall is treated with a fusible material which enters the transverse division between the upper and lower portions of the base and after being fused and baked, presents a substantially invisible seam which when coated presents an 15 esthetic and ornamental appearance. In arrangements where the upper and lower portions of the base telescopically engage for substantially the entire depth of the base, the cemented joint is entirely invisible when the base is viewed 20 in side elevation. The restricted ink pool into which the dip pen may be inserted may be molded integrally with the lower portion of the base. The principles of my invention may be carried out in various embodiments and the form set 25 forth herein is to be considered in the illustrative sense and not in the limiting sense.

Referring to the drawing in detail, reference character 1 indicates generally the base of the desk set of my invention comprising a lower 30 portion 2 and an upper portion 3 which are cemented together at their interengaging peripheries by suitable fusible material indicated at 4 in Figs. 2 and 5. The lower portion 2 of the base 1 is provided with a recessed reservoir 5 for containing the ink pool into which the dip 35 pen is adapted to be inserted. The upper peripheral edge of the recessed reservoir 5 is beveled as indicated at 6 which allows the angularly disposed wall of the integrally molded pen receiving socket 16 to extend downwardly into the recessed reservoir 5 without obstruction. The lower base portion 2 is provided with an annular ledge 7 within the limits of which the recessed reservoir 5 is formed and above which the peripheral shoulder 8 on the lower portion 2 of the base projects.

The upper portion of the base 3 is provided with an annular depending wall 9 which telescopically engages within the peripheral shoulder 8 and extends toward the annular ledge 7. The upper portion 3 of the base is provided with a central circular top 10 from which there depends a central cylindrical portion 11. The central cylindrical portion 11 is recessed as indicated at 12, the recess 12 terminating in a shoulder 13. The internal bore of the central depending cylindrical portion 11 is screw threaded as indicated at 14 for receiving screw threads 23 formed on the neck of the ink bottle 22 in the 50 inverted position illustrated in Fig. 2. The upper portion of the base 3 is provided with an integrally formed vent 15 serving as a pressure equalizing port in the hydrostatic operation of the desk set. The dip pen receiving socket is formed 55 integrally with the upper portion of the base 3 as represented at 16. The pen receiving socket projects upwardly from the upper portion 3 of the base as indicated at 17 for receiving the dip pen which I have shown generally at 26. The 60 pen receiving socket 16 comprises the upwardly projecting integral portion 17 which is substantially frusto-conical in shape, the cylindrical portion 19, the frusto-conical portion 20, and the restricted cylindrically apertured portion 21 65 through which the pen point 30 of the dip pen

is adapted to be projected. The pen holder 26 has a peripheral extremity 27 thereon and a rounded end portion 29 spaced therefrom by means of the interposed cylindrical portion 28 of the pen holder. The rounded end portion 29 and 5 the peripheral extremity 27 of the pen holder coact to substantially close the socket of the pen guide when the dip pen is in position as represented in Fig. 2. The pen receiving socket is thus substantially closed at all times when the 10 pen holder is not being carried in the hand of the writer. Accordingly, dust and foreign matter are excluded from the pool of ink 31 in the recessed reservoir 5.

The ink bottle 22 has the screw threads 23 15 thereof engaged with the integrally formed screw threads 14 in the upper portion 3 of the base. A peripheral abutment 23a on the neck of the ink bottle serves as a stop for supporting the ink bottle 22 with respect to the shoulder 13 in the 20 central recess 12. The neck of the ink bottle 22 has a restricted aperture 24 therein through which a restricted flow of ink under hydrostatic pressure is supplied to the pool of ink 31 from the supply of ink in the bottle 22. A suitable 25 protective and ornamental cover 25 is provided over the ink bottle 22. To facilitate the mounting of the desk set on a supporting surface, I may provide adhesive pads shown generally at 30 32.

In the manufacture of the desk set shown in Figs. 1-6, the lower portion of the base 2 is telescopically fitted about the annular depending wall 9 with the fusible material 4 therebetween. The parts thus prepared are subjected 35 to a fusing and baking operation which results in the fusing of the joint between upper portion 3 and lower portion 2 of the base. This joint is substantially invisible. Then the base is dipped or sprayed or otherwise coated with ornamental 40 glaze or pigment, which enters the seam at the annular joint and the joint becomes wholly invisible and the base appears as a single unitary member. A pleasing and esthetic appearance is provided because a streamlined effect is obtained by ornamenting the surface of the upwardly projecting integral wall 17 of the pen receiving socket, which ornamented surface continues without interruption throughout the entire cylindrical side wall of the base 1. 50

The screw threaded end of the ink bottle 22 is engaged in the screw threads molded into the upper portion of the base structure to a position in which the flange on the ink bottle abuts with the shoulder on the upper portion of the base structure. The cylindrical cover member is then inserted over the ink bottle 22 and the hydrostatic desk set is ready for operation. Because of the relationship of the pen receiving socket with respect to the pool of ink below the 60 restricted orifice of the ink supply bottle, a continued supply of ink may be depended upon into which the point of the dip pen is inserted from time to time during writing operations. The pressure equalizing port 15 insures a continuous 65 supply of ink from the ink bottle to the pool beneath the restricted orifice 24 under control of hydrostatic pressure.

I have found the improvements of my invention highly practical and efficient in operation 70 but I realize that modifications may be made and I intend no limitations on the invention except as may be imposed by the scope of the appended claims.

What I claim as new and desire to secure by 75

Letters Patent of the United States is as follows:

1. A desk set comprising an ink bottle, a pair of circular coacting, coextensive and connected sections constituting a substantially cylindrical base, one of said sections being internally recessed centrally of said section for receiving a pool of ink and the other of said sections being centrally screw threaded for receiving said ink bottle in inverted position, and a pen guide in said last mentioned section for directing a dip pen into the pool of ink in said first mentioned section, said set being substantially balanced on the vertical axis of said substantially cylindrical base.
- 15 2. A desk set comprising an ink bottle, a pair of circular coacting, coextensive and interengaging members superimposed one with respect to the other and connected to form a substantially cylindrical base for said ink bottle, one of said members having an internal recess centrally therein for receiving a pool of ink and the other of said members being centrally screw threaded for supporting said ink bottle in inverted position for delivering ink directly to the internally recessed portion of said first mentioned member, and a guide for a dip pen formed integrally with said second mentioned member for directing a dip pen into the pool of ink in said first mentioned member, said desk set being substantially balanced on the vertical axis of said substantially cylindrical base.
- 30 3. A desk set comprising an ink bottle, a pair of circular coacting coextensive members superimposed one with respect to the other and connected to form a substantially cylindrical base, one of said members being internally recessed centrally of said member to provide a pool for ink, the other of said members providing a support for an ink bottle said inverted position centrally of said base for delivering ink directly to the pool of ink in said first mentioned member, and a dip pen guide formed integrally with said second mentioned member and extending at a substantially acute angle with respect to the axis of the inverted ink bottle for directing a dip pen into the pool of ink in said first mentioned member, said base and ink bottle being substantially balanced on the vertical axis of said substantially cylindrical base.
- 45 4. A desk set comprising an ink bottle, a pair of circular coacting coextensive members superimposed one with respect to the other, one of said members being internally recessed centrally of said member to provide a pool for ink, the other of said members providing a support for an ink bottle said inverted position centrally of said base for delivering ink directly to the pool of ink in said first mentioned member, a peripheral depending projection on said second mentioned
- member extending into an annular recess in said first mentioned member, means uniting said members to form a rigid substantially cylindrical base, and a dip pen guide formed integrally with said second mentioned member and extending at an angle with respect to the axis of the inverted ink bottle for directing a dip pen into the pool of ink in the first mentioned member, said base and ink bottle being substantially balanced on the vertical axis of said substantially cylindrical base.
- 5 10 5. A base for a desk set comprising a bottom base member of circular contour having an annular stepped wall for providing a coaxial recess of varied depth; a top base member of circular contour equal in diameter to said bottom base member and having an annular coaxial projection adjacent the periphery for engagement with the annular stepped wall of said bottom base member, a central bore, and an annular coaxial projection surrounding said bore and adapted to project into the recess in said bottom base member, means for uniting said bottom and top base members to form a cylindrical substantially enclosed base for said desk set, means for mounting an ink bottle in inverted position in the base in said top base member, and a pen guide in said top base member for directing a dip pen into the central portion of the recess in said bottom base member.
- 15 20 6. A base for a desk set as defined in claim 5, wherein said top base member includes a plane annular portion surrounding said bore on the outer face of said member; said plane portion constituting a shoulder for supporting the ink bottle mounted in said bore, and adapted to engage the peripheral edge of a cylindrical cover for said ink bottle.
- 25 30 7. A base for a desk set as defined in claim 5, wherein said top and bottom base members are formed of ceramic material and said means for uniting said base members comprises a seam of fused material disposed between said member at the peripheral abutting portions thereof.
- 35 40 8. A base for a desk set as defined in claim 5, wherein said pen guide extends obliquely from a near central position within said base to a near peripheral position above said base, within the limits of the radius of said cylindrical base, and is formed integrally with said top base member and with the annular coaxial projection surrounding the bore in said member.
- 45 50 9. A base for a desk set as defined in claim 5, wherein said means for mounting an ink bottle in said top base member includes screw threads formed in the wall of the bore in said top base member adapted to engage screw threads on the neck portion of the ink bottle for mounting the bottle in inverted position.
